Filed Apr. 7, 1975, Ser. No. 565,690

Term of patent 14 years

Int. Cl. D23—01

U.S. Cl. D23—4

FIG. 2

FIG. 3

FIG. 4

FIG. 5

FIG. 1 is a perspective view of an underdrain for water filtration system showing my new design;

FIG. 2 is an end elevational view looking from the left of FIG. 1;

FIG. 3 is a perspective view, on an enlarged scale, of one of the lateral units shown in FIG. 1, with a portion broken away for convenience of illustration;

FIG. 4 is an end view looking from the left end of FIG. 3 but on a smaller scale; and

FIG. 5 is another end view of FIG. 3 looking from the right thereof also on a smaller scale.

The fragmentary broken line showing of a filtration basin in FIG. 1 is for purposes of illustration only.

I claim:

The ornamental design for an underdrain for water filtration system, substantially as shown and described.
